UNITED STATES PATENT OFFICE.

JAMES J. QUINN, OF CHESTER, PENNSYLVANIA.

MILK-BOTTLE LOCK.

1,360,578.

Specification of Letters Patent. Patented Nov. 30, 1920.

Application filed April 28, 1920. Serial No. 377,325.

To all whom it may concern:

Be it known that I, JAMES J. QUINN, a citizen of the United States, residing at Chester, in the county of Delaware and State of Pennsylvania, have invented certain new and useful Improvements in Milk-Bottle Locks, of which the following is a specification.

This invention relates to a lock for milk or other bottles or any other article and has for its purpose to provide means whereby the bottles of milk delivered to houses, apartments etc. may be securely locked to prevent theft in the early morning hours. Another purpose of the invention is to provide a device of this character which may be easily and quickly manipulated, and one which is of few parts.

After milk has been delivered it is very frequently stolen by pedestrians on their way to work in the early morning, and it also often happens that customers who have received their milk refuse to pay for the same, claiming that it was stolen, and it is to prevent such occurrences as these that I have devised a unique locking device which I will now proceed to describe in detail, reference being had to the accompanying drawings in which:

Figure 1 is a side elevation of the device shown in connection with a conventional door, the arm being partly in section to more clearly show the resilient tongue.

Fig. 2 is a fragmentary sectional view showing the connection between the bottle sleeve and locking arm, and

Fig. 3 is a plan view of the device on a reduced scale.

The numeral 1 designates a bottle sleeve which is preferably made of metal and which is slightly tapered thereby conforming with the taper of milk bottles and preventing their removal upwardly. For the purpose of saving metal the sleeve may be provided with cut-out portions 2.

The bottle sleeve 1 is also provided with a horizontal slot 5 and passing therethrough is the locking arm 3, which has a down turned flange 6 on its inner end thereby securely but loosely connecting the sleeve and arm. A resilient tongue 7 is provided on the locking arm 3 and is preferably struck up therefrom.

The lower edge of the sleeve 1 may be curved upwardly as shown at 9, thereby conforming roughly with the shape of the

ordinary sill 11 of the door 10. This curvature is, of course, by no means essential and it may be noted here that my locking device operates equally well whether or not the door is provided with a sill.

In operation, the neck of the bottle is passed upwardly through the lower end of the sleeve and then when the bottle is placed on the floor the sleeve slips down until the bottom of the bottle and sleeve are flush or substantially so. The locking arm is then inserted under the lower edge of the door, the resilient tongue being depressed by the door edge until it has passed beyond it, when it will spring upwardly and prevent the device from being withdrawn provided the door remains closed. Briefly stated, the resilient-tongue locks the sleeve to the door, and the bottle is locked in the sleeve by the tapering effect.

To remove the bottle it is only necessary to open the door and slip the device from under the free edge thereof; or the device may be released by depressing the resilient member 7 with the foot, or otherwise; and then opening the door.

If desired the locking arm may be provided with an aperture for the purpose of suspending it in a convenient position for access by the milkman.

While I have described the sleeve as tapering, it is to be understood that this is only illustrative, and that the sleeve may be of any shape that will prevent the upward removal of a bottle or other receptacle. Further it is obvious that the sleeve and locking arm may be made integral, without departing in any sense from my invention.

It is also obvious that any locking means capable of being passed under a door and then engaging the door to prevent its removal, may be substituted for the resilient tongue shown and it is therefore not my intention to be limited thereto.

The device has been particularly described as a means for locking bottles, but it will be apparent that it is equally well adaptable to use as a locking means in connection with any other article.

Having fully described my invention, what I claim as new and desire to secure by Letters Patent is:

1. A device of the character described including an article holding element, an arm attached thereto, an inclined resilient tongue attached to said arm, the arm and tongue

being capable of insertion under the edge of a closed door.

2. A device of the character described including a bottle holding element, an arm attached thereto, locking means secured to the arm, said locking means being capable of insertion under the edge of a closed door.

3. A device of the character described including a bottle holding element, an arm attached thereto, and an upwardly inclined resilient tongue attached to said arm, the arm and tongue being capable of insertion under the edge of a closed door.

4. A device of the character described including a bottle holding element, an arm loosely connected thereto, and a resilient tongue struck up from said arm.

5. A device of the character described including a bottle sleeve, said sleeve being so shaped as to prevent the upward removal of the bottle, and locking means attached to the sleeve, said locking means being capable of insertion under the edge of a closed door.

6. A device of the character described in-

cluding an upwardly tapering bottle sleeve, an arm attached to said sleeve and locking means attached to the arm adjacent the free end thereof.

7. A device of the character described including an open ended upwardly tapering sleeve, an arm attached to said sleeve, and an upwardly inclined resilient tongue attached to the arm.

8. A device of the character described including an open-ended upwardly tapering sleeve, said sleeve provided with a slot, a flanged arm engaged within said slot, and an upwardly inclined resilient tongue struck from said arm.

9. A device of the character described including an open-ended upwardly tapering sleeve, said sleeve provided with a slot, a flanged arm engaged within said slot, and an upwardly inclined resilient tongue struck from said arm, said sleeve having a cut-away portion substantially conforming with the curvature of a door sill.

JAMES J. QUINN.
